(57) **CLAIM**

I claim the ornamental design for a string guide for musical instruments, as shown and described.

DESCRIPTION

FIG. 1 is a perspective view of a string guide for musical instruments showing the new design, as viewed from the front, right, and top.

FIG. 2 is a perspective view thereof, as viewed from the front, left, and bottom.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof; and,

FIG. 9 is a perspective view thereof showing the device in use, sandwiched between the strings and the headstock of a guitar.

The evenly spaced broken lines shown in the figures depict unclaimed subject matter and/or environmental structure and form no part of the claimed design. The dot-dash lines shown in the figures represent a boundary of the claimed design and form no part thereof.
